UNITED STATES PATENT OFFICE.

JOSEPH DICK, OF NEW YORK, N. Y.

STOCK-MEMORANDA TABLET.

SPECIFICATION forming part of Letters Patent No. 424,184, dated March 25, 1890.

Application filed October 7, 1889. Serial No. 326,160. (No specimens.)

To all whom it may concern:

Be it known that I, JOSEPH DICK, of New York city, in the county and State of New York, have invented a new and useful Stock-
5 Memoranda Tablet, of which the following is a full, clear, and exact description.

My invention relates to an improved stock-
memoranda tablet, and has for its object to
provide a tablet upon which a record may
10 be conveniently kept of the various articles
of stock which may be exhausted by sale or
use.

A further object of the invention is to pro-
vide a tablet upon which the memoranda of
15 articles wanted may be grouped and rendered
plainly visible, and also wherein when the
articles have been supplied the record of the
wants may be quickly and conveniently can-
celed.

20 The invention consists in the novel con-
struction and combination of the several parts,
as will be hereinafter fully set forth, and
pointed out in the claims.

Reference is to be had to the accompanying
25 drawings, forming a part of this specification,
in which similar figures of reference indicate
corresponding parts in all the views.

Figure 1 is a front elevation of the device.
Fig. 2 is a longitudinal section on line $x-x$ of
30 Fig. 1. Fig. 3 is a transverse section on line
 $y-y$ of Fig. 1. Fig. 4 is a perspective view of
one of the cover-slides detached. Fig. 5 is a
35 partial front elevation of a slightly-modified
form of the device, and Fig. 6 is a perspective
detail view of the slide employed in connec-
tion therewith.

The prime object of the invention is to
construct a tablet adapted for use in stores,
hotels, restaurants, kitchens, &c., provided
40 with a series of columns and a series of cover
or indicating slides capable of being moved
from one column to another. When such a
tablet is employed and the last of any article
or articles has been used, the slide or slides
45 covering the name in the want column is
withdrawn from said column and made to
cover the name produced—for instance, in
the central column or columns, which, for con-
venience, I designate "stock-columns." Thus
50 when the intermediate columns are used as
stock-columns the want-columns, which are

shown as outer columns in the drawings, con-
stitute market or order memoranda.

The memoranda-tablet is preferably con-
structed of metal, and consists, ordinarily, of 55
a back plate 10 and a front plate 11. The
side and top edges of the back plate 10 are
bent upward and over upon the body to form
a housing or slideway 12, in which housing or
slideway the front plate 11 is slid, and the 60
lower end of the front plate is bent down-
ward and upward over the bottom edge of
the back plate, as illustrated at 13 in Fig. 2.
By this means the two plates are readily and
economically united, and in order that one 65
plate shall not slide over the other the hous-
ing or upturned edges 12 of the back plate
are compressed to a certain degree upon the
contacting edges of the upper or front plate.
The front face of the back plate 10 is prefera- 70
bly colored or made white, for instance, and
the upper or front plate 11 is divided longi-
tudinally into a series of columns 14 and 15,
each column being provided with a series of
transverse slideways 16 by producing in the 75
upper or front plate 11 a series of preferably
rectangular openings, the openings of one
column being separated from the openings in
the next column by longitudinal strips of un-
cut metal 17. 80

In the slideways of the intermediate col-
umns 15 the names of the various articles of
stock are produced in any approved manner
upon the front face of the back plate 10, and
in the slideways of the want-columns the 85
names of the articles of stock are duplicated
in the order in which they are arranged in
the next intermediate column. Thus, for in-
stance, if the word "Ale," as shown in the
drawings, appears in the first slideway of the 90
left-hand intermediate or stock column, the
same word is made to appear in the first slide-
way of the left-hand want-column, and should
the word "Mops," for instance, appear in the
upper slideway of the right-hand intermediate 95
or stock column the same word is printed
upon the back plate 10 and caused to appear
at the upper slideway of the right-hand want-
column.

In the slideways 16 indicating or cover 100
slides 18 are held to move laterally, one of
said slides being illustrated in detail in Fig.

4, each slide consisting, preferably, of a metal plate wider and longer than the slideways, struck up at the center from end to end to form essentially a convexed outer and a concaved inner surface. Each plate is provided at each end with a narrow arm 19, which projects upward at a right angle from the body. The uncut metal strips 17 are preferably transversely struck up in alignment with the 10 slideways to admit of the ready passage of the slides.

Usually four columns are employed, the two outer columns being headed by the word "Wanted" or "Wants," and the two intermediate columns being used as stock-columns, as heretofore stated; but this order may be reversed if found desirable, or more columns may be used. The slides in the right-hand outer column are so placed that the arm 19 at 15 one end will normally contact with the strip 17, dividing the intermediate column therefrom, the opposite arm 19 being made to contact with the outer edge of the column, whereby one arm travels in the slideway of the outer 20 or want column and the other in the horizontally-aligning slideway of the next inner or stock column. The same arrangement is carried out with reference to the left-hand want column and the stock-column next thereto. 25 Each slide is preferably painted black, and in operation the slides are normally made to cover or conceal the names of the articles in the want-columns, thereby exposing the names of the articles in the stock-columns. 30 Should it be necessary to order beans, the stock having been exhausted, the slide in the left-hand column registering with the word "Beans" printed in the stock-column is slid over the word in the latter column, thereby 35 exposing the same word in the want-column; and if onions are wanted and the arrangement of the names of the articles is preserved, as in the drawings, the slide is drawn from the right-hand want-column over the word 40 "Onions" in the stock-column, exposing said word thereby in the want-column. Thus a doubly registry is obtained, since the names of the goods wanted appear plainly in the want-column and are essentially erased from 45 the stock-column.

At the top of the tablet I preferably swivel a screw 20, whereby the device may be securely attached to the wall or other vertical support, and upon the lower end at each side 50 another swivel may be placed or an ear may be formed for the reception of a screw, whereby the lower portion of the device may be secured to its support; but I desire it to be distinctly understood that I do not confine 55 myself to the precise means illustrated for securing the device in a perpendicular position, as the same may be varied without departing from the spirit of the invention; nor do I confine myself to any particular material in 60 the construction of the device, metal being preferred, however, as heretofore stated.

It will be observed that in a grocery, for in-

stance, the device described is very useful, as when the entire stock of any article has been exhausted, or nearly so, the clerk or grocer 70 may make a memorandum of the fact by moving one of the slides to disclose the name of said article in the want-column, thus erasing it from the stock-column. The store-keeper is thereby enabled to give a drummer 75 or salesman of a wholesale-house without any trouble and at a moment's notice an entire list of all the articles that need replenishing, and the housekeeper, by referring to such a tablet, is enabled at all times to give a correct 80 order to the tradesman calling for the same.

I desire it to be further understood that I do not confine myself to producing the names of the articles upon the back plate and covering and uncovering the same by slides, as 85 if in practice it is found desirable the front face of the back of the device may be made opaque and the names of the articles be stenciled, printed, or otherwise produced directly upon the slides, as shown in Fig. 5, one of 90 said slides being illustrated in Fig. 6, in which it will be observed that the body of the slide is perfectly flat.

When the device is constructed as shown in Fig. 5, the slides are normally retained in 95 the stock-columns and moved to the want-columns to make the memoranda.

Having thus described my invention, I claim as new and desire to secure by Letters Patent—

1. A stock-memoranda tablet divided into want and stock columns, each having a series of openings, the openings in one column being in alignment with the openings in the other column and provided with a series of 105 slides for exposing the names of the articles of merchandise to view either in the want or stock column, substantially as described.

2. A stock-memoranda tablet consisting of a back plate having the articles of merchandise produced thereon in aligned columns, a front plate divided into want and stock columns and having a series of aligned openings, and a series of slides for alternately closing said openings, so as to expose to view 115 either in the want or stock column the names of the articles of merchandise on the back plate, substantially as described.

3. A stock-memoranda tablet consisting of a back plate having the names of articles of merchandise produced on its front face in longitudinal columns, a front plate divided into want and stock columns having a series of opposite openings, and a series of slides having a convex outer surface and provided 125 with outwardly-extending projections, one projection working in the opening of the want column and the other in the opening of the stock-column, substantially as described.

JOSEPH DICK.
